US00D970944S

(12) **United States Design Patent** (10) **Patent No.:** **US D970,944 S**
Dai (45) **Date of Patent:** **** Nov. 29, 2022**

(54) **SHELF PARTITION**

(71) Applicant: **SHENZHEN YIHONG TECHNOLOGY CO., LTD**, Shenzhen (CN)

(72) Inventor: **Yi Dai**, Shenzhen (CN)

(73) Assignee: **SHENZHEN YIHONG TECHNOLOGY CO., LTD**, Shenzhen (CN)

(**) Term: **15 Years**

(21) Appl. No.: **29/823,598**

(22) Filed: **Jan. 18, 2022**

(51) LOC (13) Cl. **06-06**

(52) U.S. Cl. **USPC** **D6/706**

(58) **Field of Classification Search**

USPC D6/672, 682, 705, 705.2, 706; D8/380-381; D3/319

CPC A47B 67/10; A47B 65/15; A47B 88/00; A47B 88/90; A47B 88/975; A47F 5/005; A47F 5/0068; A47F 5/105; A47F 3/06

(57) **CLAIM**

The ornamental design for a shelf partition, as shown and described.

DESCRIPTION

FIG. 1 is a perspective view of a shelf partition showing my new design;

FIG. 2 is another perspective view thereof;

FIG. 3 is another perspective view thereof;

FIG. 4 is a front elevational view thereof;

FIG. 5 is a rear elevational view thereof;

FIG. 6 is a left side elevational view thereof;

FIG. 7 is a right side elevational view thereof;

FIG. 8 is a top plan view thereof;

FIG. 9 is a bottom plan view thereof; and,

FIG. 10 is a perspective view of the shelf partition where the shelf partition is in a configuration of use.
